UNITED STATES PATENT OFFICE

CHARLES WILLIAM BHOSYS, OF NEW YORK, N. Y.

METHOD OF PRODUCING MULTIPOSE PICTURES

Application filed August 16, 1928. Serial No. 300,127.

This invention relates to the art of photography and more particularly refers to improvements in the production of photographic compositions obtained by combining 5 a plurality of exposures of the same subjects.

The primary object of this invention is to provide a novel and improved method of producing photographic compositions in the nature of groups of individuals or other photographic subjects, consisting of the same subject or subjects photographed at different times and in different positions on a single negative, without showing any line of demarcation between the different exposures.

15 Another object is to provide a novel and improved method of producing photographic compositions of the character mentioned where some of the exposures are co-related in order to produce a cumulative effect of 20 movement or interaction.

A further object is to provide a novel method of a simple character for producing photographic compositions in the nature of groups obtained by various exposures of 25 the same subject or subjects on a single negative, where some of the exposures are in overlapping relation to one another producing a realistic effect as if two individuals or subjects had actually been photographed at 30 the same time while one was partly or totally in front of the other.

Other objects and advantages of the present invention will more fully appear as the description proceeds and will be set forth 35 and claimed in the appended claims.

Double or multipose exposures of the same subject on the same negative have heretofore been produced by limiting the field of projection of the objective within the camera 40 to a portion of the negative's surface, and by shifting the negative to a successive position so as to expose a new portion thereof for each exposure.

The result is a series of two or three or 45 more separate pictures of the same subject on the same negative; but the exposures thus obtained are sharply defined and independent of one another, and being totally unrelated do not produce a single 50 photographic composition such as for in-

stance, a group of people photographed together against a single background and in a single exposure.

The chief aim of this succession of fractional exposures of a negative is to effect 55 savings of material and time in producing various photographs, which need not necessarily be of the same subject; but there is no question in this case of producing photographic compositions having any special 60 novelty or artistic value.

The present invention refers to a process 65 whereby various exposures of the same subject are taken on the same negative at different times and in different relative positions where the negative is entirely exposed to photographic action at each exposure and does not have to be shifted from one position to another. By using a special type 70 of background and by paying proper attention to certain conditions governing the actinic value of various portions of the subject being photographed, it becomes possible to produce novel, puzzling and artistic 75 effects giving the illusion of groups of individuals or subjects being photographed at the same time in different positions and postures, said individuals or subjects all having the same features while only one individual or subject has actually been photographed. 80

My invention which is applicable both to 85 still and to moving pictures, will be more clearly understood by referring to the accompanying drawings in which:

Fig. 1 illustrates an individual exposure 85 of a photographic group composition;

Fig. 2 shows another exposure of the same subject in a different pose;

Fig. 3 illustrates a still different exposure 90 of the same subject in a different pose;

Fig. 4 illustrates the combined group effect obtained by the three exposures of Figs. 1, 2, 3;

Fig. 5 is a plan view illustrating the various positions of the subject in relation to 95 the camera in the three exposures;

Fig. 6 is a fragmentary front view of a special type of photographic background which may be used in carrying my invention into practice;

Fig. 7 is a side view in elevation thereof;

Fig. 8 is a front view illustrating two different co-related positions of the same subject producing together a photographic composition;

Fig. 9 is a plan view of the same; and

Fig. 10 is a front view in elevation of an adjustable standard which may be used as a reference medium in determining a pose of the subject in relation to its pose in a preceding or following exposure.

Figs. 1 to 5 illustrate the manner of producing a multipose photographic composition according to my invention, the final result being illustrated in Fig. 4. In the same it is seen that the same person has been photographed three times in three different poses combining to form a group which gives the illusion of being the result of the photographing by a single exposure of three persons arranged in a group, said persons having similar features but being in different postures and occupying different positions.

The group comprises one picture 20 of a girl standing in proximity of a table 21, while in another picture 22 the same subject is shown sitting with the table in front of her, and in another picture 23 at the right still the same subject is shown standing, pouring tea in a cup 24 resting on the table, from a pot 25 held in her right hand.

This third picture partly overlaps the second one, the left hand 26 of the girl concealing part of the table and her right hand 27 and the pot held thereby, concealing part of the body of the subject in the second picture. There is no line of demarcation defining the three separate exposures, and the effect produced creates the perfect illusion of having been obtained at a single exposure.

The individual exposures are separately illustrated in Figs. 1, 2, 3, where it is seen that the subject which is designated by the same reference characters used in Fig. 4, occupies the same relative positions with respect to the table 21 as shown in said Fig. 4.

All three exposures are taken against a black or non-actinic background 28 shown in Fig. 5, and the camera 29 is set in a position which remains the same for all three exposures.

The non-actinic character of the background causes the sensitized surface of the film or plate to be affected exclusively by the subject at each exposure, while the rest of the space within the range of the objective remains perfectly blank insofar as the sensitized surface is concerned.

Thus in Fig. 1 the portion of the plate which is not affected by the non-actinic background remains capable of being affected by the subject when the subject is moved to the

right to the position of Fig. 2; and similarly that portion still more to the right which has not been affected due to the non-actinic character of the background is still available for the taking of a third picture such as illustrated in Fig. 3.

Assuming that there are no other objects or subjects in the picture, the picture would now be complete, except that an explanation must be given of the reason why some parts of the subject may be made to appear as overlapping other parts within the range of a former exposure. This is done by causing the parts which are overlapping to have a higher actinic value with respect to the sensitized surface than the parts which are overlapped thereby; also by taking the exposure with the higher actinic value subsequently to an exposure having a less actinic value.

The actinic value of a given subject or of given parts of a subject with respect to the sensitized surface of the plate is determined by color and by distance.

For instance, assuming that the subject in one exposure wears a dark dress and in another exposure a light colored dress, if parts of the subject in the two exposures are overlapping, the lighter surfaces will affect the negative more than the darker surfaces and will appear as overlapping the same; the same thing happens for instance, if the bare hand of the subject in one exposure appears in the same portion of the field as the surface of the dark dress taken in a different exposure.

When there is a marked difference in color between the two overlapping surfaces, the subject may be placed at practically the same distance from the camera in the two exposures if desired; it is preferable however, and in many cases imperative that the exposure having a less actinic value be taken first.

In this manner the lighter surfaces will appear as overlapping the darker ones. However, a true effect of relative proportions will be lacking, because when a subject is overlapping another it is naturally closer to the camera and appears in somewhat enlarged proportions; therefore in order to obtain a truer effect it is better to place the subject nearer to the camera in the second or overlapping exposure.

This in its turn assists in improving the results, because as stated, distance is also a factor in determining the tone value of various parts of the picture. For instance, assuming that the subject wears the same dress for both exposures, the mere fact that in the second exposure it is placed from one to two feet nearer the camera is sufficient to establish a sharp distinction between the tone values of the two exposures so that whatever parts in the second exposure are

overlapping parts of the first exposure will appear clearly defined in the picture as such, entirely blotting out whatever impression the surfaces behind may have made on the sensitized surface.

Thus referring to Figs. 4 and 5, it is seen that parts of the picture taken in the third exposure are placed in front of parts of the picture taken in the second exposure; and 10 being nearer the camera the same will appear as shown providing a true depth effect for the finished composition such as would be obtained if two different exposures were actually photographed at the same time in 15 the same positions.

Another factor which deserves consideration in the production of these multipose pictures, is the corelation which it at times required between the positions of the subject 20 in different exposures in order to produce a predetermined result.

Thus it will be noted that in the group under consideration, a table 21 is used together with a cup 24 lying on said table and 25 a tea pot 26 from which tea is about to be poured into said cup by the subject in the third exposure acting as a hostess for the subject in the second exposure acting as a guest.

30 The medium used in order to set the various elements in their proper relation is in this case the table 21 which also forms a part of the picture; and the result illustrated in Fig. 4 is obtained by covering the 35 table with a black non-actinic cloth 30 during the first and third exposures and uncovering said table for the second exposure.

The effect of the non-actinic covering for the table is to render the same absolutely inactive and blank insofar as the sensitized surface is concerned.

40 The space occupied by the cloth is rendered active during the second exposure because at such time the parts of the subject 45 under the table must not be concealed, and because at some time or other during the operation the table must be shown anyway if the ultimate result is to be achieved; and by once more covering the table during the 50 third exposure, the impression previously created upon the sensitized plate remains unaffected and the cup 21, pot 25 and hand 26 of the subject will appear as overlapping parts of the table and of the body of the subject respectively, appearing in the previous 55 exposure, due to the higher actinic value of said cup, pot and hand as explained.

If desired a finishing touch may be given 60 in order to improve the artistic value of the composition by printing the positives with the aid of a transparent background or vignette such as currently used by photographers in portrait work.

65 On the other hand certain photographers prefer to use painted backgrounds, and this

is particularly true when some special effect is desired calling for a special composition.

I have therefore devised a special construction of painted background whereby my 70 method may also be carried into practice by applying substantially the same principles upon which the fundamental idea is based.

Referring to Figs. 6, 7, 8, 9 it will be seen that my improved background comprises a rear panel 31 which covers the entire field and which has a black or non-actinic surface, and a plurality of panels 32, 33, 34 together forming the painted background, which may 80 be independently placed in front of the rear panel or removed therefrom.

In the example shown 32, 33 designate two side panels and 34 designates a center panel, and it is seen that the two side panels are 85 slightly ahead of the center panel and have their inner edge portions 35, 36 overlapping the edge portions 37, 38 of the center panel.

When a multipose picture is produced using this type of background, each exposure 90 is taken with the subject standing in front of the corresponding panel of the painted background while the remaining panels are removed so as to expose the non-actinic surface 95 behind; the exposed panel therefore becomes a part of the finished picture.

When another part of the composition is produced by a succeeding exposure, the subject is placed in another position in front of the corresponding painted panel, and the 100 other panels including the one which was previously exposed are withdrawn so as to expose the non-actinic surface of panel 31; and so on.

The ultimate result is a composition where 105 not only the subject is portrayed in different poses which may be co-related or partly overlapping, but also the background is portrayed to give the true illusion of a group taken in front of the same.

110 The various panels composing the background can be of any suitable form or design as long as the painted ones can be moved on and off the range of the objective for the purpose stated. A convenient construction is shown in the drawings partly in Fig. 7, where it is seen that the various panels are of a flexible type and are mounted on rolls 39, 40, 41 upon which they can be wound or from which they can be unwound after the fashion in which ordinary shade rollers or stage settings are operated.

115 In Fig. 8 is shown a composition comprising two exposures of a girl, portraying two girls shaking hands with each other.

This co-relation of the two exposures makes it necessary to pay special attention to the relative positions of the two clasped hands in each exposure in order to make 120 sure that a correct result will be achieved.

In cases of this kind it is best to make use of some reference medium or gauge whereby the correct position of the two co-related portions of the picture can be determined.

- 5 For instance, in Fig. 10 I show a stand 42 provided with an adjustable standard 43 which may be set at any desired height by means of a set screw 44, and said stand is also shown in dotted lines at 42' in Fig. 8: 10 In the same it will be seen that the right hand of the subject in each exposure is caused to rest upon the top of the standard 43 which has previously been adjusted at the proper height. The stand itself however, 15 must not appear in the picture, and therefore it is used merely as a gauge to determine the height of the hand before each exposure and it is removed before each picture is actually taken. If desired however, in 20 one of the exposures, the stand may be used as a support for the hand provided it is painted dead black or is concealed by a black or non-actinic colored cloth, and provided it does not conceal part of the subject. 25 When a painted field such as shown in Figs. 6 to 9 is used, the central panel should preferably be a little darker than the side panels so as to produce an effect of depth in the background, this being in conformity with the current practice in the use 30 of painted backgrounds where the central portion is generally darker. Furthermore the side sections or panels should overlap the central panel in order to produce an effect 35 of continuity without sharp lines of demarcation. It is obvious from the foregoing description that in carrying my invention into practice some of the operative details may vary to a certain extent from those 40 shown and described without departing from the inventive idea. The drawings should therefore be considered as being intended for illustrative purposes only, and not in a limiting sense. 45 I accordingly reserve myself the right to carry my invention into practice in all those ways and manners which may enter, fairly into the scope of the appended claims.

I claim:

- 50 1. The method of producing a multipose picture of a given subject on a single negative, which consists in first photographing the subject against a portion of the background, using a non-actinic surface at least 55 for the remainder of the background within the range of the objective but without the scope of the exposure, then photographing the subject against another portion of the background, using a non-actinic surface for 60 the portion of the background previously used, parts of said subject being made to appear as overlapping other parts thereof in the finished picture, by being given a higher actinic value in relation to the sensitized surface 65 face of the negative used.

2. The method of producing a multipose picture of a given subject on a single negative, which consists in first photographing the subject against a portion of the background, using a non-actinic surface at least 70 for the remainder of the background within the range of the objective but without the scope of the exposure, then photographing the subject against another portion of the background, using a non-actinic surface for 75 the portion of the background previously used, parts of said subject being made to appear as overlapping other parts thereof in the finished picture, by placing said overlapping parts nearer the camera in the later exposure.

3. The method of producing a multipose picture of a given subject on a single negative, which consists in first photographing the subject against a portion of the background, using a non-actinic surface at least 80 for the remainder of the background within the range of the objective but without the scope of the exposure, then photographing the subject against another portion of the background, using a non-actinic surface for 85 the portion of the background previously used, the second exposure being co-related to the first by determining both exposures in relation to a common reference 90 medium.

4. The method of producing a multipose picture of a given subject on a single negative, which consists in first photographing the subject against a portion of the background, using a non-actinic surface at least 95 for the remainder of the background within the range of the objective but without the scope of the exposure, then photographing the subject against another portion of the 100 background, using a non-actinic surface for the portion of the background previously used, the second exposure being co-related to the first by determining both 105 exposures in relation to a common reference medium, said reference medium being shielded by a 110 non-actinic covering in all the exposures but one, and being uncovered in said one exposure, when used as an element of the 115 finished composition.

5. The method of producing a multipose picture of a given subject on a single negative, which consists in first photographing the subject against a portion of the background, using a non-actinic surface at least 120 for the remainder of the background within the range of the objective but without the scope of the exposure, then photographing the subject against another portion of the background, using a non-actinic surface for 125 the portion of the background previously used, the second exposure being co-related to the first by determining both exposures in relation to a common refer- 130

- ence medium, parts of said subject being made to appear as overlapping other parts thereof in the finished picture, by being given a higher actinic value in relation to the sensitized surface of the negative used.
6. The method of producing a multipose picture of a given subject on a single negative, which consists in first photographing the subject against a portion of the background, using a non-actinic surface at least for the remainder of the background within the range of the objective but without the scope of the exposure, then photographing the subject against another portion of the background, using a non-actinic surface for the portion of the background previously used, the second exposure being co-related to the first by determining both exposures in relation to a common reference medium, parts of said subject being made to appear as overlapping other parts thereof in the finished picture, by placing said overlapping parts nearer the camera in the later exposure.
7. The method of producing a multipose picture of a given subject on a single negative, which consists in first photographing the subject against a portion of the background, using a non-actinic surface at least for the remainder of the background within the range of the objective but without the scope of the exposure, then photographing the subject against another portion of the background, using a non-actinic surface for the portion of the background previously used, the second exposure being co-related to the first by determining both exposures in relation to a common reference medium, said reference medium being shielded by a non-actinic covering in all the exposures but one, and being uncovered in said one exposure, when used as an element of the finished composition, parts of said subject being made to appear as overlapping other parts thereof in the finished picture, by being given a higher actinic value in relation to the sensitized surface of the negative used.
8. The method of producing a multipose picture of a given subject on a single negative, which consists in first photographing the subject against a portion of the background, using a non-actinic surface at least for the remainder of the background within the range of the objective but without the scope of the exposure, then photographing the subject against another portion of the background, using a non-actinic surface for the portion of the background previously used, the second exposure being co-related to the first by determining both exposures in relation to a common reference medium, said reference medium being shielded by a non-actinic covering in all the exposures but one, and being uncovered in said one exposure, when used as an element of the finished composition, parts of said subject being made to appear as overlapping other parts thereof in the finished picture, by placing said overlapping parts nearer the camera in the later exposure.
9. The method of producing a multipose picture of a given subject on a single negative, which consists in first photographing the subject against a painted portion of the background, using a non-actinic surface for the remainder of the background within the range of the objective but without the scope of the exposure, then photographing the subject against a painted portion of background covering said non-actinic surface, after removing the painted portion previously used so as to uncover a non-actinic surface for the corresponding portion of the background.
10. The method of producing a multipose picture of a given subject on a single negative, which consists in first photographing the subject against a painted portion of the background, using a non-actinic surface for the remainder of the background within the range of the objective but without the scope of the exposure, then photographing the subject against a painted portion of background covering said non-actinic surface, after removing the painted portion previously used so as to uncover a non-actinic surface for the corresponding portion of the background, part of one of said painted portions overlapping part of the other and being nearer to said objective.
11. The method of producing a multipose picture of a given subject on a single negative, which consists in successively taking pictures of said subject by separate exposures, while said subject occupies different positions in relation to the background, leaving both the camera and the negative always in the same position, and each time exposing the negative in its entirety to the photographic action, the background providing for each exposure a non-actinic surface at least for such parts thereof which although within the range of the objective, remain without the scope of the said exposure.
12. The method of producing a multipose picture of a given subject on a single negative, which consists in successively taking pictures of said subject by separate exposures, while said subject occupies different positions in relation to the background, leaving both the camera and the negative always in the same position, and each time exposing the negative in its entirety to the photographic action, the background providing for each exposure a non-actinic surface at least for such parts thereof which although within the range of the objective, remain

without the scope of the said exposure, and
objects linking one pose to another being
shielded by a non-actinic covering in all the
exposures but one, and being uncovered in
5 said one exposure, when used as elements of
the finished composition.
